Edgar F. Miller

UNITED STATES PATENT OFFICE.

GUSTAV A. MATTER, OF BROOKLYN, NEW YORK.

WINDOW-SCREEN.

1,145,603.

Specification of Letters Patent.

Patented July 6, 1915.

Application filed August 14, 1914. Serial No. 856,742.

To all whom it may concern:

Be it known that I, GUSTAV A. MATTER, a citizen of the United States, and residing at Brooklyn, in the county of Kings and State 5 of New York, have invented certain new and useful Improvements in Window-Screens, of which the following is a specification, such as will enable those skilled in the art to which it appertains to make and use the 10 same.

This invention relates to window screens and the object thereof is to provide an improved device of this class designed for use in connection with either the top or bottom 15 sash or in connection with both sashes; a further object being to provide a screen for windows which may be counter-sunk in the bottom of a window frame, or in the top of a window frame, and with which the corresponding sash will be automatically connected in the operation of closing said sash so that it will follow the sash and close the 20 space opened thereby when the sash is opened; and with this and other objects in view, the invention consists in a window 25 screen or screens constructed and applied as hereinafter described and claimed.

The invention is fully disclosed in the following specification, of which the accompanying drawing forms a part, in which the separate parts of my improvement are designated by suitable reference characters in each of the views, and in which:—

Figure 1 is a sectional, inside view of the 35 bottom part of a window frame provided with my improvement and showing the bottom portion of the bottom sash, part of the construction being broken away; Fig. 2 a section on the line 2—2 of Fig. 1; Fig. 3 a section on the line 3—3 of Fig. 2, and; Fig. 4 a section on the line 4—4 of Fig. 1.

In the drawing forming part of this specification, I have shown at *a* the bottom portion of a window frame having the usual 45 window opening *a*² at the sides of which are the inner beads or strips *a*³, the central beads or strips *a*⁴, and the outer bead or strip *a*⁵. The bottom sash *b* is movable in the space *a*⁶ formed by the beads or strips *a*³ and *a*⁴ and the top sash, not shown, is movable in the space *a*⁷ formed by the beads or strips *a*⁴ and *a*⁵, and the window frame is also provided, in the construction shown, with a bottom, transverse bead or strip *a*⁸.

In the practice of my invention, I form 55 in the bottom sill *a*⁹ of the window frame, and under the space *a*⁶ in which the lower sash *b* is movable, a chamber *a*¹⁰ and placed therein is a suitable metal or other casing *c* containing a screen roller *d* on which is 60 wound a screen *d*².

In the construction shown, one end of the roller *d* is provided with a helical spring *e*, one end of which is secured to said roller and the other to the end of the casing *c* at *e*², but 65 said roller may be made in any way, or similar to other spring rollers of this class.

The casing *c* is provided with a longitudinal opening *c*² in the top thereof, and the spring *e* is placed in a separate chamber 70 formed by a supplemental end plate *c*³ in the casing *c*, said end plate being provided with a vertical slot *c*⁴ and in assembling these parts, the roller is passed down into the casing *c* and the ends thereof provided 75 with bearings *d*³.

The free end of the screen *d*² is connected with a transverse plate *f*, centrally of the bottom thereof as shown at *f*², and this plate is provided with upwardly directed 80 fingers *g*, two of which are employed, and these fingers are adapted to enter corresponding recesses *g*², in the bottom bar *b*² of the bottom sash and said fingers are provided at their ends with outwardly directed 85 nose-pieces *g*³. The bottom rail *b*², of the bottom sash is also provided with deep transverse chambers or recesses *h* which open 90 forwardly or inwardly and in which are pivoted arms *i*.

The arms *i* are pivoted at their inner ends as shown at *i*² and placed at the outer sides of said arms are springs *j*, which normally hold them in operative position as shown in Fig. 3, and said arms are provided with handles *i*³ which project forwardly from the bottom rail of the bottom sash, and the arms *i* engage the fingers *g* or the nose-pieces *g*³ thereof, to lock the screen *d*² in connection 95 with the bottom sash.

When the screen is not in use, the plate *f* rests on the top of the casing *c* with the fingers *g* projecting upwardly, and when the sash is closed or lowered into its closed position, the fingers *g* pass upwardly into the 105 bottom rail *b*² of said sash, in which position the arms *i* are moved outwardly by said fingers, after which said arms are forced in-

wardly by the springs j and into the operative position shown in Fig. 3.

With this construction, the raising of the bottom sash will carry the screen d^2 with it and the space below the sash will be closed by said screen and no insects can enter the building beneath the sash. If it is desired to not use the screen, all that is necessary in raising the sash, is to move the arms i outwardly so that they will be disengaged from the fingers g and the screen will remain in the casing c when the sash is raised.

Although I have shown my improvement applied only to the bottom sash and the bottom of the window frame, it will be understood that the same may be applied to the top sash and to the top of the window frame if desired, all that is necessary being to counter-sink the casing c in the top of the window frame and to connect the screen with the top sash by the same means employed for connecting it with the bottom sash.

My invention is not limited to the exact details of construction herein shown and described and changes therein and modifications thereof, may be made within the scope of the appended claim, without departing from the spirit of my invention or sacrificing its advantages.

Having fully described my invention,

what I claim as new and desire to secure by Letters Patent, is:—

A window, the frame of which is provided in the bottom thereof with a countersunk casing which is directly under the bottom sash, said casing being open at the top, a spring roller mounted in said casing, a screen one end of which is connected with said roller and the other with a transverse plate adapted to rest on the top and close said casing, and means for automatically connecting the bottom sash with said plate when said sash is closed, consisting of horizontal and vertical recesses in the bottom rail of the sash and which open through the front and bottom thereof, spring operated arms pivoted in the recesses which open through the front of said rail, and finger pieces connected with said plate and adapted to enter the recesses which open downwardly through the bottom of said rail and to engage said arms.

In testimony that I claim the foregoing as my invention I have signed my name in presence of the subscribing witnesses this 18th day of February 1914.

GUSTAV A. MATTER.
